UNITED STATES PATENT OFFICE.

FRED A. LUKE, OF KALISPELL, MONTANA.

STEAM-ENGINE.

1,320,629.

Specification of Letters Patent.

Patented Nov. 4, 1919.

Application filed June 13, 1919. Serial No. 303,861.

To all whom it may concern:

Be it known that I, FRED A. LUKE, a citizen of the United States, residing at Kalispell, in the county of Flathead and State 5 of Montana, have invented certain new and useful Improvements in Steam-Engines, of which the following is a specification.

This invention relates to rotary engines, and more particularly to a rotary steam engine or turbine, the primary object being to 10 provide an apparatus of this character which will operate with no loss of steam and which will employ complementary rotors having steam pockets provided with properly inclined walls against which the steam 15 acts for rotating the rotor in the proper direction.

A further object of this invention is the production of a device of this character 20 which consists of comparatively few parts and is simple in construction but durable and well adapted to withstand the rough usage to which devices of this character are ordinarily subjected.

25 For a full description of the invention and the advantages and merits thereof, reference is to be had to the following description and accompanying drawings, in which:—

Figure 1 is a side elevation of the engine 30 constructed in accordance with my invention.

Fig. 2 is a transverse section taken approximately on the line 2—2 of Fig. 3.

Fig. 3 is a horizontal section taken on the 35 line 3—3 of Fig. 1.

Fig. 4 is a section taken on the line 4—4 of Fig. 1.

Fig. 5 is a fragmentary section taken approximately on the line 5—5 of Fig. 4.

40 Fig. 6 is a detail section taken on the line 6—6 of Fig. 2.

Referring to the drawing, wherein is illustrated the preferred form of my invention, in which like numerals of reference indicate 45 like or corresponding parts throughout the several views, the turbine housing 1 is of circular formation and is mounted upon a pedestal 2 and has its open end provided with removable closure plates 3 and 4. Ex-

50 tended centrally through the turbine housing and through suitable bearings in the closure plate is a shaft 5 the central portion of which is provided with the keys 6. Mounted upon the shaft and engaged by 55 the keys to turn therewith are the complementary rotors 7 and 8 which form the tur-

bine within the housing 1. The interior of the housing is provided with an annular centrally located recess 9 and each member 7 and 8 is equipped with an annular flange 60 projected into the said annular recess as shown to advantage in Figs. 3 and 4. The faces of the rotors 7 and 8 are spaced apart and these rotors are also longitudinally slideable on the shaft. Studs 10 carried by one 65 rotor project into recesses formed in the adjacent face of the other rotor and coil springs 11 surround the stud and engage the adjacent faces of the rotors to force them away from each other until such 70 time as the steam is admitted. As shown in Figs. 2 and 6, each rotor is provided with a plurality of steam pockets 13 which are circumferentially spaced apart and are tapered as shown in Fig. 6 by providing a straight 75 wall 14 and the angular wall 15 terminating at the bottom wall 16. Four of these pockets are provided in each rotor and the rotors are positioned on the shaft so that the pockets in the two rotors will be out of 80 axial alignment. In other words, the pockets in one rotor are attached so as to be in axial alignment with a point midway between two pockets in the other rotor.

Each plate 3 and 4 is provided with an 85 inlet opening 17 to which the steam pipe 18 is connected. The steam pipe includes the two branches 19, the ends of which are joined to the inlet 17, the branches 19 receiving the steam from the main supply pipe 90 18. A feed pipe 20 is projected from the center of the steam pipe through the wall of the housing and into the space between the rotors, so that steam will be received in this space to urge the rotors away from each 95 other and press their faces into tight contact with the adjacent faces of the plates 3 and 4. Packing glands may be provided on the inner portions of the rotors where the openings for the shaft are provided to prevent leakage of steam through the shaft 100 openings in the rotors. Obviously packing glands may be provided for this purpose wherever required.

Each plate 3 and 4 is also provided with 105 an exhaust opening 21, this opening being located in each plate so as to receive the exhaust steam from the pockets 12 prior to the alinement of the pocket with the intake opening 17. It will be noted that the 110 walls are also arranged in the same manner as are the walls of the steam pocket,

one wall being inclined as indicated at 22 and the other wall being straight as shown at 23 whereby the steam is directed into the pockets at the required angle.

5 In operation, the steam is supplied through the steam supply pipe 18 and into the branch pipe 19 and through the extension pipe 20. The steam from the extension pipe 20 enters the space between the 10 rotors and forces the rotors outwardly since they are slidably mounted on the shaft 5. This makes a pipe connection with the outer plate 3 and the steam through the branch pipe 19 enters the intake openings 17 in 15 the plate and is thereby conducted into the pocket 13. Since the intake openings 17 are in axial alinement as shown in Fig. 3 and the pockets in the two rotors are out of axial alinement it will be obvious that only one 20 pocket will be supplied with steam at a time and the supply of steam will be alternately furnished to the pockets in the two rotors as the device is actuated. The steam entering one of the pockets will 25 expand as it is emitted from the opening 17, and thereby cause a pressure to be exerted on the straight wall 14 of the pocket to impart rotary movement to the rotor. This continues in each of the pockets while steam 30 is supplied so that the rotary movement of the rotors is continued and power is thereby transmitted to the drive shaft 5.

The foregoing description and accompanying drawings have reference to what 35 might be considered to be the approved or preferred form of my invention. I desire it to be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent, is:—

45 1. In a steam turbine, the combination of a drive shaft, two independent rotors mounted for sliding movement on the drive shaft and keyed thereto to rotate with the drive shaft, each disk having a series of steam 50 pockets formed therein, the said pockets opening in the outer faces of the rotors,

spring means interposed between the inner faces of the rotors to maintain the rotors in spaced relation to provide a space between the rotors, and means for supplying steam 55 to the pockets of the rotors and to the space between the said rotors for action on the walls of the pockets and for maintaining the rotors in spaced relation.

2. In a steam turbine, the combination 60 of a drive shaft, a housing having the drive shaft extended therethrough, plates provided with central bearings to receive the said drive shaft, the said plates being equipped with openings, the said rotors each 65 having a series of pockets adapted to register with the inlet openings in the plates, means to maintain the rotors in spaced relation, steam pipes to supply steam to the inlet openings, and to the space between 70 the rotors, the pockets in the said rotors being out of axial alinement with respect to the pockets in each rotor, the said inlet openings being in axial alinement.

3. In a steam turbine, the combination of 75 a housing having a centrally located shaft equipped with keys, plates fastened to the ends of the housing and provided with bearings to support the shaft centrally in the housing, rotors mounted on the shaft within 80 the housing and keyed with the said keys to rotate with the shaft and permit longitudinal sliding movement of the rotors on the shaft, a series of pockets formed in each 85 rotor, the pockets in one rotor being out of axial alinement with the pockets in the other rotor, each of the said plates having inlet openings in axial alinement and adapted to register with the said pockets in the 90 rotors, a steam supply pipe having branches 95 connected to the inlet openings and an extension extended centrally through the housing and into the space between the rotors to supply steam to the space between the rotors for urging the latter against the said plates.

In testimony whereof I affix my signature in presence of two witnesses.

FRED A. LUKE.
